UNITED STATES PATENT OFFICE.

FREDERICK C. ROCKWELL, OF HARTFORD, CONNECTICUT.

INCANDESCENT-ELECTRIC-LAMP BASE.

SPECIFICATION forming part of Letters Patent No. 488,222, dated December 20, 1892.

Application filed December 26, 1891. Serial No. 416,162. (No model.)

To all whom it may concern:

Be it known that I, FREDERICK C. ROCKWELL, a citizen of the United States, residing at Hartford, in the county of Hartford and 5 State of Connecticut, have invented certain new and useful Improvements in Incandescent-Electric-Lamp Bases, of which the following is a full, clear, and exact specification.

This invention relates to the portion of an 10 incandescent electric lamp at the base of the globe in which the leading wires of the filament are connected with the circuit wires.

The object of the invention is to provide an 15 ornamental, cheap, simple and efficient base which may be made key or keyless, of insulating material in two parts that are readily and easily united or taken apart, also a base in which the connections and conducting parts are so separated that they cannot be 20 connected by gathering moisture or dirt and thus short circuit a current passing through the base.

Referring to the accompanying drawings: Figure 1 is a vertical section through a base 25 provided with a key. Fig. 2 is a similar section of the same on a different plane, with a part broken away. Fig. 3 is a plan looking into the socket or cup part of the base. Fig. 4 is a plan of the globe part of the base; and 30 Fig. 5 is a vertical section of a base without any connections or conductors.

In the views 1 indicates the end of the globe of an incandescent electric lamp of any pattern or make, having the usual filament and leads. 35 To the end of the globe is secured a bottom 2 which is molded, cast, or pressed of rubber composition or any insulating materials, in one piece with a cavity to receive the globe. If the end of the globe to which the bottom is 40 to be attached is re-entrant, as shown, a diaphragm or partition 3 may be formed across the cavity dividing it into two chambers. The upper part of the bottom is also preferably formed with a cavity the walls of which, when 45 pressed, are provided with a screw thread, but this thread, if desired, may be made on the exterior of the bottom. Pieces 4, of brass, copper, or other suitable conducting material, are molded into the bottom when it is formed, 50 and the lead wires to the filament connected to these pieces. It is preferred that these

pieces should have a slight spring and to permit this a space 5 is left beneath them when the bottom is formed.

A concave or socketed shell 6, cast, molded, 55 pressed, or otherwise formed of insulating composition similarly to the bottom, provided at its open end with a thread, is secured to the bottom so that the completed base is practically a single piece of insulating material. It 60 is preferred that this shell or socket shall have an integral dividing partition 7, so that when the shell is screwed to the bottom two chambers are formed in the interior. Through the closed end of the shell, which may or may not 65 have a projecting hub, a perforation is made to each chamber for the entrance of the circuit wires, and in this end so as to project into each chamber when the shell is formed are molded connected posts 8 and 9, of conducting material, as brass or copper. These 70 posts are preferably bent from a single piece of metallic tube, the posts 8 being slotted so that they may receive and grasp the bared ends of the circuit wires to form the connection without further manipulation. One of the posts 9 projects downward so as to come 75 into contact with one of the pieces 4 in the bottom when the parts are screwed together, while the other post, if it is a key socket, 80 bears a tube 10 of conducting material. This tube has a sliding movement on the post and is kept from rotation by means of a pin 11 that passes through the post and a slot in the tube. A spring 12 normally tends to draw 85 and hold the tube to the closed end of the shell, and from the side of the tube a lug 13 projects into the plane of the key. The key is preferably formed of a rod 14 supported in 90 perforations in the walls, with the usual handle, and a piece of insulating material 15 of oblong cross-section in the path of the lug 13, so that when the longer diameter of the insulating piece is in contact with the lug the tube will be forced toward the bottom and 95 make contact with one of the pieces 4, but when the shorter diameter is in contact with the lug the tube under the influence of the spring is drawn away from the contact in the bottom. The insulating portion of the key is 100 loosely mounted upon the rod and rotated by means of a pin 16 projecting from the rod into

a slot in the insulating piece, so that when the key is turned to break the circuit the contact is broken suddenly.

If it is desired to make a double break both 5 sets of posts 9 may be provided with the sliding tubes described and the key made to extend across to the other wall of the shell through the partition, or the partition may be removed, and for a keyless socket both 10 posts are made long enough to extend to the contacts in the bottom, and neither bear sliding tubes, the shells and bottoms however being made similarly for both key and keyless bases. When the shell and bottom are screwed 15 together the partition divides the interior into two entirely separated chambers so that there can be no accidental contact between the opposite parts of the circuit, and so that no moisture or dirt can collect between the 20 two and form a circuit which will shunt the current. This is particularly desirable for use in connection with high tensions or series lamp currents which cannot be short circuited through the base described. The 25 advantages of a base formed integral of plastic material are obvious; it may be made of high non-conductivity to prevent any possibility of shocking or short circuiting through the base; the conducting parts can be easily 30 permanently molded into position; there is no need of separate insulating pieces; there are no metallic screws to be fastened or to work loose; and the base may be made in two parts which are formed upon the same dies 35 whether or not it is to be provided with a key. Of course the plastic molded material when pressed in dies can be highly ornamented to produce a fine artistic though cheap finish.

I claim as my invention:—

40 1. A base for an incandescent electric lamp consisting of a bottom formed of a single piece secured to the globe and bearing con-

ducting pieces, and a shell formed of a single piece having two longitudinal chambers, with one end closed and the other secured to the 45 bottom, with wire perforations through the closed end to each chamber also bearing conducting pieces, substantially as specified.

2. A base for an incandescent electric lamp consisting of a bottom formed of a single 50 piece of insulating material secured to the globe, with conducting pieces molded therein, and provided with a thread and a shell formed of a single piece of insulating material with one end closed and the other threaded and 55 screwed onto the threaded bottom, with conducting pieces also molded therein, substantially as specified.

3. In combination with a base for an incandescent electric lamp consisting of a battery 60 formed of a single piece of insulating material bearing conducting pieces, a shell formed of a single piece of insulating material with conducting posts molded therein, one being bent and having its shank molded into the 65 insulating material leaving projecting ends, one of which carries the movable member of a switch and the other being split to receive a circuit wire, substantially as specified.

4. A base for an incandescent electric lamp 70 consisting of a bottom formed of a single piece of insulating material secured to the globe and bearing conducting pieces, and a shell formed of a single piece of insulating material bearing conducting posts adapted to 75 receive the circuit wires, conducting tubes sliding on said posts, a key for drawing the tubes in one direction and springs for drawing the tubes in the opposite direction, substantially as specified.

FREDERICK C. ROCKWELL.
